UNITED STATES PATENT OFFICE

1,955,753

MACHINE FOR OPERATING UPON THE
SOLES OF SHOESAxel Arnold Lawson, Beverly, Mass., assignor to
United Shoe Machinery Corporation, Paterson,
N. J., a corporation of New Jersey

Application April 4, 1933, Serial No. 664,312

9 Claims. (Cl. 12—18)

This invention relates to improvements in machines for operating upon the soles of shoes and is herein illustrated as embodied in a machine for rounding, channeling, or rounding and channeling the soles of shoes prior to permanently sewing or otherwise securing the soles to the shoes.

Rounding and channeling machines of the type most commonly employed are provided with 10 cooperating work gripping and feeding members which are adapted to engage the projecting sole or bottom margin of a shoe and feed it progressively past a rounding or trimming knife, an example of such a machine being the rounding and channeling machine disclosed in United States Letters Patent No. 1,030,606, granted June 25, 1912, upon application of F. H. Perry. In order to provide for the satisfactory feeding of 15 sole margins of different thicknesses, in the machine just referred to, one of the work gripping and feeding members is yieldingly pressed toward the other by spring mechanism which is capable of being adjusted to maintain a substantially uniform pressure upon sole margins of different thicknesses, that result being obtained by 20 the use of a lever for transmitting the tension of the spring to the gripping member, the arrangement of the lever and the spring being such that the leverage is varied inversely with respect to 25 variations in the tension of the spring so as to counteract or compensate for changes of spring tension. The uniform tension mechanism disclosed in the above patent has not, however, been generally adopted in commercial rounding and 30 channeling machines probably because the beneficial results intended to be accomplished were liable to be lost on account of improper adjustment of the mechanism by the operator of the machine. Most rounding and channeling machines now in commercial use, therefore, have no 35 mechanism which will function to maintain a substantially uniform pressure of the work gripping and feeding members upon sole margins which are thicker in one portion than in another, 40 although the advantages of such mechanisms are well recognized particularly in the case of soles having spring heels, such soles being frequently twice as thick in the heel portions as at the shanks and foreparts. In the absence of any 45 uniform pressure mechanism, the feeding of such a sole is likely to be interrupted or seriously interfered with as a result of the increased pressure with which the sole is gripped by the feeding members when a relatively thick portion of the 50 sole margin reaches the latter.

In view of the foregoing, one object of the present invention is to provide, for use in machines of the above-mentioned character, improved mechanism for maintaining a substantially uniform pressure of the work gripping and feeding 60 members upon the work, which will be particularly adapted for convenient attachment to existing machines and which is designed for reliable and effective operation independently of any manual adjustment thereof by the operator of 65 the machine.

To the accomplishment of this object, one feature of the present invention consists in a self-contained or unitary attachment for a machine for operating upon shoe soles comprising 70 a bracket adapted to be attached to the frame of the machine, a lever pivotally mounted upon said bracket and adapted to be connected with a work-engaging member, for example a work gripping and feeding member, and a spring connected at one end to said lever and at its opposite end to said bracket and permanently disposed relatively to said lever to vary the leverage inversely to variations in the tension of the spring resulting from variations in work thickness, 75 thereby enabling the lever to transmit substantially uniform pressure to said work-engaging member regardless of variations in work thickness. The above-mentioned bracket upon which the illustrated uniform pressure mechanism is 80 mounted is so constructed that it is adapted to be applied to a rounding and channeling machine to take the place of a removable member regularly provided to serve as an abutment for the spring which supplied the work gripping pressure and 85 which is discarded when the present attachment is applied to the machine and the bracket is adapted to be attached by screws which engage within tapped holes already formed in the machine frame for receiving screws for holding the above-mentioned abutment member in place. Thus the present mechanism may be attached 90 to existing machines without the necessity of performing any measuring or machining operations.

While it is important that the pressure with which the work is gripped by the feeding members shall be maintained substantially uniform upon all portions of the sole margin of each shoe operated upon, it is also important that provision should be made whereby the work gripping pressure may be varied in accordance with the characteristics of different kinds of soles upon which it may be desired to operate, it being desirable to grip the margin of a relatively soft 105 110

sole, such for example as a rubber sole, with less pressure than in the case of a relatively hard sole, such as a sole composed of a fine quality of leather, in order to insure maximum efficiency 5 in the feeding of the work. The invention, accordingly, is further concerned with the provision of improved means for adjusting the initial tension of the spring which supplies the work gripping pressure. As herein illustrated, this 10 improved means comprises a manually adjustable mechanism adapted to be set in a plurality of positions of adjustment for predetermining the amount of pressure to be exerted upon the work.

15 The invention will now be explained with reference to the accompanying drawing, in which

Fig. 1 is a view in side elevation of so much of a rounding and channeling machine as is necessary to illustrate the application of the present 20 invention thereto; and

Fig. 2 is a detailed front elevational view of a portion of the mechanism shown in Fig. 1, illustrating particularly the improved means for adjusting the initial tension of the spring which 25 supplies the gripping pressure to the work.

The machine shown in the drawing is a rounding and channeling machine which is adapted to perform a rounding or trimming operation only upon the sole or bottom margin of a shoe, such, 30 for example, as the shoe A which, as indicated in Fig. 1, is provided with an outsole B having a so-called spring heel portion C which is substantially thicker than the shank and forepart portions of the sole. The illustrated machine is provided with a reciprocating rounding or trimming knife 10, and cooperating work gripping and feeding members comprising a sole support 12, and a feed plate 14 which are arranged to engage opposite sides of the margin of the outsole 35 B to support the latter while it is being cut by the knife 10 and which are vibrated to advance the sole margin one step after each cutting stroke of the knife. These parts are of the same construction and have the same general mode of 40 operation as that of corresponding parts of the machine disclosed in the above-mentioned Letters Patent No. 1,030,606, to which reference may be had for particulars of construction and operation not herein specifically described. For an 45 understanding of the present invention it will be necessary also to know that, as in the machine of the patent referred to, the work support 12 of the illustrated machine is carried by a carrier slide 16 which is mounted upon an oscillatory support 18 and that the support 18 is formed upon the front end of a shaft 20 which is mounted to rock and to move longitudinally in horizontal bearings 22 formed in the frame 24 of the machine, so that the work support 12 may vibrate 50 in the direction of feed of the work to cooperate with the vibratory feed plate 14 in the feeding of the work and may also move toward and from the feed plate 14 to accommodate variations in work thickness.

55 As herein illustrated, the slidable rockshaft 20 is acted upon by means of spring mechanism which constantly urges the shaft endwise in a direction to press the work support 12 forwardly toward the feed plate 14 so that the margin of a shoe sole interposed between the support 12 and the feed plate 14 will be firmly gripped by the latter, and which permits the work support 12 to yield backwardly or causes it to move forwardly as may be required to accommodate variations in the thickness of the sole margin at dif-

ferent parts of the shoe being operated upon. Moreover, the spring mechanism just referred to is designed to press the work support 12 against the work with a substantially uniform pressure regardless of the thickness of the material being operated upon and thereby avoid any interference with the feeding of the work. To this end, as herein shown, the spring mechanism comprises a coiled spring 30, a lever 32 which is acted upon by the spring, and a horizontal rod 34 the rear end of which is engaged by the upper extremity of the lever 32 and the front of which fits within an axial bore in the rear portion of the rockshaft 20. As shown, the lower end of the lever 32 is pivoted at 36 to a bracket 38 the upper portion of which is rigidly secured by means of screws 40 to the rear bearing 22 for the rockshaft 20. The upper end of the spring 30 is engaged within a notch 42 formed in a stud 44 which is rigidly secured by means of a nut 46 to a lug 48 formed on the lever 32. The stud 44 is formed with a shoulder 49 which seats against a finished flat surface on the lug 48 when the nut 46 is tightened thereby positively locating the notch 42 relatively to the lever 35 to insure accurate compensation for changes in 100 spring tension caused by variations of work thickness. The lower end of the spring 30 is engaged within a notch 50 in a stud 52 which projects from a disk 54 formed on a stub shaft 56 which is mounted to turn in a bearing formed in the lower 105 extremity of the bracket 38, the stud 52 being eccentric to the axis of the shaft 56 so that turning of the shaft in its bearing will adjust the stud 52 toward or from the stud 44 to expand or contract the spring 30 and thus to vary its tension. 110 For the purpose of turning the shaft 56 to adjust the tension of the spring 30, a hand lever 58 is pinned to the shaft 56 and a latch 60 is pivoted at 62 to the hand lever 58 and is urged by a spring 64 in a direction to maintain it in engagement 115 with one of a plurality of notches 66 formed in a segmental surface 68 at the lower extremity of the bracket 38 so as to lock the stud 52 in different selected positions of adjustment. By releasing the latch 60 and turning the hand lever 58 120 the initial tension of the spring 30 may be adjusted to vary the pressure with which the sole margin is gripped according to the character of the material of which the sole is composed.

In operation the work support 12 may be retracted relatively to the feed plate 14 to permit the margin of a sole or shoe bottom to be introduced between those members by depression of a foot treadle 70 which, as shown, is connected by a rod 72 with one arm of a bell crank lever 74 130 which is pivoted at 76 to the frame of the machine and the other arm of which is arranged to engage a lug 78 formed on a sleeve 80 which is fixed upon the rockshaft 20. Upon release of the treadle 70 the force of the spring 30 will be transmitted through the lever 32, the rod 34, the slidable rockshaft 20, the carrier 18, and the slide 16 to the work support 12, thereby causing the sole margin to be gripped between the support 12 and the feed plate 14 with a pressure determined by 140 the tension of the spring 30. Advantageously the maximum pressure may be as high as forty pounds when the eccentric stud 52 is positioned as shown in the drawing while the minimum pressure may be as low as ten pounds when the eccentric pin 52 has been adjusted into a position determined by engagement of the latch 60 with the uppermost of the notches 66. Whatever initial tension may be imparted to the spring 30 by adjustment of the eccentric stud 52, however, the

- resulting pressure with which the work is gripped by the feeding members 12 and 14 will not be materially effected by rearward movement of the member 12 resulting from an increase in the thickness of the sole margin because, as the member 12 and the rockshaft 20 are displaced rearwardly and as the rod 34 swings the lever 32 backwardly, the increased tension resulting from the stretching of the spring 30 will be counteracted 5 inasmuch as the force of the spring will then be applied to the lever 32 at a more acute angle. In other words, the length of the moment arm of the pull exerted by the spring will be shortened and the leverage through which the tension of 10 the spring is transmitted to the sole support will be diminished. In the construction shown the spring 30 and the lever 32 are relatively proportioned and arranged so that any variation in the tension of the spring resulting from movement of 15 the lever 32 in response to variation in work thickness will be counteracted or compensated for to such an extent as to insure that the pressure exerted by the sole support 12 upon the sole margin will remain substantially uniform regardless 20 of any variation in the thickness of the sole margin. Thus, in the case of the shoe shown in the drawing, the margin of the outsole will be gripped between the work feeding members 12 and 14 with substantially the same pressure 25 whether those members are gripping the relatively thin portions at the shank and forepart of the shoe or whether they are gripping the relatively thick portion of the sole margin at the heel of the shoe. In order to secure this result it is, 30 of course, necessary that the spring 30 shall be accurately disposed in a particular relation to the lever 32 and to the axis about which that lever swings. By mounting both the lever 32 and the spring 30 upon the same fixture or bracket, as 35 herein described, and thus providing a self-contained, uniform tension device in the nature of a unit to existing machines by merely removing a cap or abutment member which is customarily 40 secured to the outer end of the rearmost bearing 45 22 and by substituting therefor the herein-described attachment. The attachment is adapted to be rigidly secured to the frame of the machine by means of the screws 40 which are constructed 50 to fit within tapped holes already provided for 55 the purpose of receiving screws for holding in place the cap above referred to.
- A machine equipped with the herein-described uniform pressure device may be adapted for maximum efficiency in feeding soles of varying degrees of firmness by adjustment of the hand lever 58 to vary the initial tension of the spring 30 and thus to cause the work feeding members to grip the sole margins with a degree of pressure which 60 is most suitable for the particular soles to be operated upon, it being understood that relatively soft soles, e. g. rubber soles, should be gripped with substantially less pressure than relatively hard soles, e. g. fine quality leather soles.
- Having described my invention, what I claim as new and desire to secure by Letters Patent of the United States is:
1. For use in a machine for operating upon the soles of shoes wherein a work-engaging member is mounted for movement to accommodate varia-
  2. For use in a machine for operating upon the soles of shoes wherein work gripping and feeding members are mounted for relative movement to accommodate different thicknesses of sole margins, an attachment comprising, in combination, a bracket adapted to be attached to the frame of the machine, a lever pivotally mounted upon said bracket, a rod mounted to slide in a bearing in said bracket with one end in engagement with said lever, said rod being adapted to be connected with one of said work gripping and feeding members, a spring connected at one end to said lever and at its opposite end to said bracket and permanently disposed relatively to said lever to vary the leverage inversely to variations in the tension of said spring resulting from variations in work thickness, thereby enabling said lever to transmit substantially uniform pressure to said work-engaging member regardless of variations of work thickness.
  3. For use in a machine for operating upon the soles of shoes wherein a work-engaging member is mounted for movement to accommodate variations of work thickness, a unitary attachment comprising, in combination, a bracket adapted to be attached to the frame of the machine, a lever pivotally mounted upon said bracket and adapted to be connected with said work-engaging member, an eccentric pin, a post mounted on said bracket for adjustment toward and from said lever, means for adjusting said post, a spring connected at one end to said lever and at its opposite end to said post and arranged to vary the leverage inversely to variations in the tension of the spring whereby said lever is enabled to transmit substantially uniform pressure to said work-engaging member regardless of variations in work thickness.
  4. In a machine for operating upon the soles of shoes, the combination with work supporting and feeding members arranged to engage opposite sides of the projecting margin of the bottom of a shoe, a bracket secured to the frame of the machine, a lever mounted upon said bracket, a rod slidable within a bearing in said bracket with one end engaged by said lever, a carrier for one of said supporting and feeding members, connections between said slide rod and said carrier, and a spring connected at one end to said lever and at its opposite end to said bracket and permanently disposed relatively to said lever to vary the leverage inversely to variations in the tension of the spring whereby the lever is enabled to transmit substantially uniform pressure through said slide rod and said carrier to cause said work supporting and feeding members to engage the work with substantially uniform pressure regardless of variations in work thickness.
  5. In a machine for operating on shoe soles, in combination, a sole support capable of yielding to accommodate variations in sole thickness, a

spring for holding the support against a sole arranged to maintain a substantially uniform pressure upon the sole regardless of variations in the thickness of the sole, and means having a plurality of different predetermined positions of adjustment for varying the tension of the spring.

6. In a machine for operating upon the soles of shoes, in combination, work supporting and feeding members arranged to engage opposite sides of the projecting margin of the bottom of a shoe, a spring arranged to cause said members to grip said bottom margin with a substantially uniform pressure regardless of variations in the thickness of the margin, means for adjusting the tension of said spring, and means for holding said adjusting means in a plurality of different predetermined positions.

7. In a machine for operating upon the soles of shoes, in combination, work feeding members arranged to engage opposite sides of the projecting margin of the bottom of a shoe, means including a spring and an eccentric pin for causing said members to grip said bottom margin with a substantially uniform pressure regardless of variations in the thickness of the margin, and means for turning said pin and for locking it in different positions of adjustment for varying the tension of said spring.

8. In a machine for operating upon the soles of shoes, in combination, a work feeding member arranged to engage one side of the projecting margin of the bottom of a shoe, a movable work support arranged to engage the opposite side of said bottom margin, a lever arranged to move said

35

work support toward said feeding member to grip the work, a spring connected at one end to said lever arranged to cause said work support to exert a substantially uniform pressure upon said bottom margin regardless of variations in the thickness of said margin, a rotatably adjustable device to which the opposite end of said spring is eccentrically connected, means for adjusting said device to vary the tension of the spring, and means for locking said device in different positions of adjustment.

9. In a machine for operating upon the soles of shoes, in combination, a frame, a work feeding member arranged to engage one side of the projecting margin of the bottom of a shoe, a movable work support arranged to engage the opposite side of said bottom margin, a bracket secured to said frame, a lever mounted upon said bracket, connections between said lever and said work support for moving the latter toward said feed member, a spring connected at one end to said lever, a manually rotatable member carried by said bracket, an eccentric pin on said rotatable member to which the opposite end of said spring is connected, said spring being arranged to cause said work support to grip said bottom margin with substantially uniform pressure regardless of variations in the thickness of said margin, a notched segment carried by said bracket, and a latch on said rotatable member for cooperating with said segment for holding said member in different positions of adjustment.
